UNITED STATES PATENT OFFICE

2,344,837

INSIDE CALIPER

Roy Lloyd Tarket, Wilmington, Calif.

Application May 24, 1943, Serial No. 488,225

1 Claim. (Cl. 33—156)

The present invention relates to new and useful improvements in inside calipers and has for its primary object to provide, in a manner as hereinafter set forth, a device of this character which is adapted to be readily used in narrow, deep and other difficult places where instruments in use at present cannot be used.

Another very important object of the invention is to provide an inside caliper of the aforementioned character comprising a novel construction and arrangement of contact points or fingers and actuating means therefor.

Other objects of the invention are to provide an inside caliper of the character described which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is an elevational view of an inside caliper constructed in accordance with the present invention.

Figure 2 is an elevational view of the instrument, taken at right angles to Figure 1.

Figure 3 is a vertical sectional view, taken substantially on the line 3—3 of Figure 1, showing the contact points or fingers in open position.

Referring now to the drawing in detail, it will be seen that the embodiment of the invention which has been illustrated comprises a barrel 1 of suitable metal, said barrel including a knurled portion 2. One end portion of the barrel 1 has formed therein a longitudinal slot 3 providing bifurcations 4.

A rod 5 is mounted for longitudinal adjustment in the barrel 1. Fixed on one end portion of the rod 5 is an elongated head 6. One end portion of the head 6 is bifurcated, as at 7. Contact points or fingers 8 have one end pivotally secured by a pin 9 between the bifurcations 7 of the head 6. The slot 3 in the barrel 1 accommodates the contact points or fingers 8. The pivoted end portions of the contact points or fingers 8 have formed diagonally therein cam slots 10. A pin 11 extending between the bifurcations 4 is engaged in the slots 10. Thus, when the head 6 is adjusted longitudinally in the barrel 1, the contact points or fingers 8 are caused to open or close.

Threaded on the other end portion of the rod 5 is a knurled adjusting knob 12. The adjusting knob

12 includes a smooth, reduced end portion 13 which is rotatable in the barrel 1, said reduced portion providing a shoulder 14 for abutting engagement with the opposed end of said barrel.

5 Adjacent the inner end of the adjusting knob 12, a bushing 15 is mounted in the barrel 1. The rod 5 is slidable through the bushing 15. Fixed on the rod 5 at a point in spaced relation to the bushing 15 is a collar 16. A coil spring 17 has one end engaged with the bushing 15 and its other end engaged with the collar 16 for yieldingly urging the rod 5 in a direction to open the contact points or fingers 8.

15 It is thought that the operation of the instrument will be readily apparent from a consideration of the foregoing. Briefly, the device is inserted in the work and the adjusting knob 12 is turned in a direction to move the rod 5 toward the contact fingers 8 under the influence of the coil spring 17. In this manner the fingers 8 are opened into engagement with the work. This is accomplished through the medium of the pin 11 in the cam slots 10 causing the fingers 8 to 20 swing on the pivot 9.

25 Of course, to swing the contact fingers 8 toward closed position, the adjusting knob 12 is turned in the opposite direction.

It is believed that the many advantages of an 30 inside caliper constructed in accordance with the present invention will be readily understood and although a preferred embodiment of the instrument is as illustrated and described, it is to be understood that changes in the details of construction may be resorted to which will fall within the scope of the invention as claimed.

35 Having described the invention, what is claimed as new is:

An inside caliper comprising a barrel, a rod 40 mounted for longitudinal adjustment in the barrel, contact fingers pivotally mounted on one end of the rod, coating means on the barrel and the fingers for opening and closing the latter upon adjustment of the rod in the barrel, a bushing 45 mounted in the barrel at an intermediate point, the rod extending slidably through said bushing, a collar fixed on the rod in spaced relation to the bushing, a coil spring in the barrel engaged with the bushing and the collar for yieldingly urging the rod in a direction to open the contact fingers, and an adjustment knob threadedly mounted on the other end portion of the rod, said adjusting knob including a reduced portion operable in the barrel and further including a shoulder for abutting engagement with the adjacent end of the barrel.

50 ROY LLOYD TARKET.
